TOWEL CABINET

August I. Hondeville, Merced, Calif., assignor to
Serv-A-Towel Manufacturing Company, San
Francisco, Calif.

Application October 23, 1933, Serial No. 694,749

19 Claims. (Cl. 312—37)

This invention relates to towel servidores for lavatories, of the character used by a number of people, such as in public buildings, employees' or customers' lavatories of large stores etc. The device is also of that character in which each user has an individual towel as distinguished from the servidores of the continuous towel or roller type.

The invention contemplates the use of pads of towels non-separable from each other and mounted against complete withdrawal from the containing cabinet as far as the user is concerned. In all such devices of this general character as have been previously used, as far as I am aware, no satisfactory and commercially economical means other than one manually operated, have been provided to dispose of and remove a used towel from sight.

I have found from experience and observation however that the majority of people after using a towel do not take the trouble to operate such means to dispose of the used towel and it remains in sight and is exposed to the view of and for possible use by a subsequent user, unless the lavatory attendant is constantly on duty to dispose of the towels as they are used. If this is not done the lavatory towel dispensing device constantly presents an unsanitary and untidy appearance.

It is therefore the principal object of my invention to remove this deficiency by providing a servidor so constructed that after the user has manipulated the device to dispense a towel and has used the same, the release of the dispensing means by such user will automatically withdraw the used towel from view. The servidor thus always presents the desired sanitary and neat appearance without any effort on the part of the user or an attendant.

Another object is to provide a device of this character in which not only the used towels but the fresh ones are normally concealed, so that there is no danger of the fresh towels becoming soiled from exposure nor can a used towel be employed more than once.

These objects I accomplish by means of such structure and relative arrangement of parts as will fully appear by a perusal of the following specification and claims.

In the drawings similar characters of reference indicate corresponding parts in the several views:

Fig. 1 is a perspective view of the servidor showing the actuating pedal partly depressed and

the cover partially opened to initially expose a towel for manipulation and use.

Fig. 2 is a perspective view of a pair of towel pads as combined and mounted in the servidor but removed from the same.

Fig. 3 is a transverse section of the servidor showing the actuating means in its normal inoperative position.

Fig. 4 is a similar view showing the position of the parts when the actuating pedal is depressed. 10

Fig. 5 is a sectional plan on the line 5—5 of Fig. 3.

Fig. 6 is a fragmentary enlarged transverse section of the device showing the control mechanism in its normal position. 15

Fig. 7 is a fragmentary sectional plan on the line 7—7 of Fig. 3 with the parts in their normal position.

Fig. 8 is a fragmentary sectional plan on the line 8—8 of Fig. 6 showing the position of the control members when the towel supporting unit is turned part way from a normal position. 20

Fig. 9 is a fragmentary transverse section showing the tilted towel supporting unit as being lowered to its normal position before rotation, but 25 after a towel has been used.

Fig. 10 is a similar view showing said unit as returned to a normal position, or before being moved from the same.

Fig. 11 is a similar view showing the unit being initially tilted. 30

Fig. 12 is a similar view showing the unit as released for rotation and about to rotate.

Fig. 13 is a fanciful elevation of the door controlling dashpot. 35

Referring now more particularly to the characters of reference on the drawings, the device comprises a rectangular vertical cabinet 1 adapted to rest on the floor and provided along the front and top with an opening 2. This is normally closed by a cover 3 of convexedly curved form, having depending ears 4 hinged onto the sides of the cabinet as at 5 so that said cover may swing back and inside the cabinet to expose the towels which may then be drawn one by one 45 through the opening as will be later seen.

A pedal lever 6 is secured on a transverse shaft 7 mounted in the cabinet at the bottom, said lever being on one side of the cabinet and pivotally connected to a link 8 which is pivoted on one end of a substantially horizontal lever L which is pivoted intermediate its ends on the adjacent walls of the cabinet. The opposite end of the lever is pivotally connected to the adjacent end of an upstanding pusher unit, the upper end of which 50

55

is connected to the adjacent cover ear 4. This unit comprises a lower link 9 extending between and connected to said lever and the cylinder C of a dashpot. The upper link 9a extends between 5 and is connected to the cover ear and to the piston P of the dashpot which is slideable in the cylinder C. A tension spring S is connected to the ear and to the cabinet and tends to maintain the cover closed. The cylinder is of course filled 10 with oil and the bleed and relief passages in the piston are arranged so that the downward movement of the piston in the cylinder is retarded while its upward movement is relatively free.

When the cover is in its lowermost position and 15 the pedal 6 is in its normal position, the piston is at the top of the cylinder, as indicated by the dotted outline in Fig. 3.

In operation a depression of the pedal 6 by the 20 user causes the pusher unit to be raised without materially affecting the position of the piston in the cylinder, causing the cover 3 to be moved to an open position against the resistance of the spring S. As soon as the depressing movement 25 on the pedal is halted the spring immediately starts to pull the cover to a closed position, but the initial opening movement of the cover places the same some distance back of the upper edge of the openings 2, as shown in Fig. 4. This gives the user ample time to pull out the towel he in- 30 tends to use before the cover has moved sufficiently toward a closed position to interfere with such grasping and pulling of the towel. The pedal is held depressed while the towel is being used as and for the reason set forth hereinafter, 35 but in the meantime the cover is restored to its closed position by the action of the spring S; the oil from the cylinder below the piston moving slowly to above the piston through the relatively small bleed hole provided therein. By the time 40 the cover is completely closed the piston occupies a position close to the bottom of the cylinder. Now when the pedal is released and allowed to resume its normal position, such movement of the 45 pedal causes the cylinder C to be moved down relative to the piston. With such movement however the oil above the piston can freely travel through the same by reason of the large relief passage therethrough which opens in a corresponding direction. The parts are then restored 50 to their original position, or in other words with the piston at the top of the cylinder, ready for another cover opening movement by a subsequent user.

Mounted inside the cabinet 1 and projecting 55 upwardly from the bottom in spaced relation to the walls of the cabinet is a rigid enclosing and mechanism supporting structure, indicated generally at 10, and terminating some distance below the top of the cabinet. Hinged in and transversely of the enclosure adjacent its front side and intermediate the top and bottom is a vertical frame 11, serving as a support for a turnable vertical shaft 12. The upper end of this shaft above the frame supports and is fixed to a horizontal 60 rectangular plate 13 from adjacent the corners of which rods 14 project upwardly, said rods being outwardly hooked on their upper ends as shown. These rods serve as guides for a towel supporting follower plate 15 having an upwardly arched member 16 in the middle which extends crosswise of the cabinet. A compression spring 17 between the plates 13 and 15 acts to force the latter upwardly. The rods 14 also serve as guides and locating means for opposed towel pads 18, the towels of each pad being permanently bound to-

gether along one edge. Each pad of towels has spaced holes 19 adjacent said edge to slidably fit over the rods; the holes of one pad engaging the back pair of rods and the holes of the other pad engaging the front pair of rods. When the towel pads are assembled for mounting in the cabinet, the individual towels of the two pads are partly folded over on top and are disposed in alternately overlapping relation to each other as shown. The arch element 16 causes the limp towels to assume 10 a similar form which facilitates the withdrawal of the uppermost towel through the opening 2, while the spring 17 causes the towels as a unit to be forced upwardly so that they abut against the hooked ends of the rods 14, which ends of course 15 limit the upward movement of the towels.

It will therefore be seen that when the pedal lever is depressed and the cover is swung back, the upper folded portion of the topmost towel of the stack is exposed for use, and is in position to 20 be easily pulled out by the user, who grasps the free edge of the folded portion and pulls the same outwardly until such outward movement is limited by the bound edge of the towel which is of course that edge nearest the front wall of the cabinet. 25

It will also be seen, owing to the opposed alternating arrangement of the sets of towels, that a pulling out of the topmost towel will not tend to pull out or disturb the next towel of the same set, since there is a towel therebetween which is connected at its end opposite to the direction of pull. Also this pulling movement on the upper towel has no tendency to disturb or drag against the adjacent towel, since due to the folded arrangement of the towels said upper towel is literally 30 peeled from engagement with the under towel rather than being dragged over the same.

The depression of the pedal also serves another purpose, as will be now explained. Projecting rearwardly from the shaft 1 is an arm 20 from 40 which a push rod 21 projects upwardly to a termination under the frame 11 at a point opposite the hinge. When therefore the pedal is depressed the rod 21 engages the frame 11 and tilts the same forwardly causing the towels to be moved close 45 to the cabinet opening where they are more accessible for manipulation by the user, as shown in Fig. 4.

Turnable on the shaft 12 is a drum 22 about 50 which is wrapped a cable 23. Fixed on the shaft 55 adjacent the drum is a ratchet wheel 24, the teeth of which are adapted to be engaged, for rotation in one direction only, by a pawl 25 yieldably mounted on the drum. The cable 23 extends from the drum over direction changing pulleys 26 mounted in the structure 10. A link 28 connects said arm with a short arm 29 projecting forwardly from the shaft 1. The other end of the cable is connected to one end of a tension spring 30, the other end of which is connected to said arm 27. 60 When the pedal is depressed therefore the arm 27 is depressed also, pulling on the cable and rotating the drum 22.

At the same time the spring 30 is placed under considerable tension both by reason of the taking 65 up of the corresponding end of the cable and by the depression of the arm to which said spring is connected. The parts are arranged so that with the full depression of the pedal the drum is rotated exactly one-half a turn, in a direction such 70 as to cause the pawl 25 to move about the ratchet wheel without rotating the same.

Fixed on the shaft 12 toward its lower end is a diametral cross arm unit 31 having oppositely depending stop pins 32, yieldably pressed down by 75

springs 33. One pin at a time normally engages an upwardly projecting fixed stop 34 mounted on the structure 10 below the frame 11. Mounted on said frame 11 immediately beyond the stop 34 in the direction of driving rotation of the shaft 12, is another stop 35 positioned to be engaged by either pin 32 at a time immediately after the latter has passed by the stop 34. Said pin is then in vertical alinement with the stop 34, as shown in Fig. 12. A spring pressed pawl arm 36 is mounted on the frame 11 and engages the pin 32 in engagement with either of said stops 34 or 35, as shown in Fig. 7, and prevents rotation of said shaft in other than the proper direction. When either pin is thus engaged with said stops the supporting structure of the towel pads will be in position so that the free edges of the towels are parallel to the cabinet opening 2.

In operation, as previously indicated, the intended user of a towel initially depresses the pedal 6 which exposes the opening 2, whereupon said user pulls on the topmost towel and draws the same through the opening. While he is thus using the towel the pedal must be held depressed. After the towel has been used it is allowed to hang down the front of the cabinet outside the opening, as shown in Fig. 4, and the user may then release the pedal. With the initial depressing of the pedal the frame 11 is raised, causing one of the stop pins 32 to be raised clear of the stop 34, so that the shaft 12 is free to rotate just sufficiently to cause said stop 32 to engage the stop 35, as shown in Fig. 9.

When the pedal is released the frame 11 is lowered by the withdrawal of the rod 21 from under the same. The stop pin 32 being then immediately above the fixed stop 34, such lowering movement of the frame 11 causes said stop 32 to be pressed upwardly until it clears the stop 35, as shown in Fig. 12. The spring 30 is then free to act to pull the drum 22 in the opposite direction from that in which it was rotated by the pull of the cable 23, causing the ratchet wheel 24 to be driven and the shaft 12 and the towel supporting structure mounted thereon, to be rotated through a half turn. This places the opposite pad of towels in position relative to the opening 2 so that the topmost towel thereon will then be in position to be pulled out with a subsequent opening of the cover 3.

At the same time as soon as the towel supporting unit starts to rotate the previously used towel, which is hanging down on the outside of the cabinet, is drawn through a slot 37 cut in the side of the cabinet at one end of the opening 2 and in depending and communicating relation therewith, as clearly shown in Fig. 1. Said used towel thus moves edgewise through the slot 37 and is returned to the interior of the cabinet; there being ample space between the walls of the cabinet and the interior structure for said towels to hang down inside without interfering. I preferably use a plurality of towel pads each having a relatively small number of towels thereon, so that as all the towels of one pad are used up the complete pad will then move around the hooked ends of the supporting rods 14 and drop of its own weight into the bottom of the cabinet. The next pad below is then of course moved up the necessary distance to take its place by reason of the action of the spring 11.

In order to facilitate the mounting of the towel pads in place by the attendant or service man, the top of the cabinet back of the cover 3 is preferably in the form of a separate hinged cover 38,

which is normally locked against being opened by an unauthorized person by suitable means, as shown at 39.

Since the cover 3 will probably move to a closed position in the manner previously set forth before the user has finished with the towel, said cover never completely closes the opening 2, in order to leave sufficient room for the movement of the towel through the slot 37 without any binding of the towel by the closed cover being had.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A towel servidor comprising a cabinet having a horizontal opening in its front wall for the withdrawal of a towel, a support in the cabinet for towels arranged in superposed stacked order, and in position relative to the opening so that the topmost one can be withdrawn through said opening, means mounting the support for rotation within the cabinet, means mounted for rotation with the support and engaging the edge of the towels nearest the opening to prevent complete removal of the towels from the cabinet, and means to rotate the support after a towel has been withdrawn from the opening; there being a slot in the front wall of the cabinet depending from the leading end of the opening relative to the direction of rotation of the support to receive the towel edgewise with such rotation and when said towel is hanging from the opening on the outside of the cabinet.

2. A towel servidor comprising a cabinet having a horizontal opening in its front wall for the withdrawal of a towel, a support in the cabinet for towels arranged in superposed stacked order, and in position relative to the opening so that the topmost one can be withdrawn through said opening, but normally spaced inwardly of the opening, means mounting the support for rotation within the cabinet, a forwardly tiltable frame supporting said mounting means, means mounted for rotation and tilting with the support for engaging the edge of the towels nearest the opening to prevent complete withdrawal of towels through the opening, releasable means to tilt the frame forwardly whereby to move the topmost towel close to the opening for withdrawal therethrough, and means controlled by and functioning with the release of said last named means to rotate the support; there being a slot in the front wall of the cabinet depending from the leading end of the opening relative to the direction of rotation of the support to receive the towel edgewise with such rotation and when said towel is hanging from the opening on the outside of the cabinet.

3. A towel servidor comprising a cabinet having a horizontal opening in its front wall for the withdrawal of a towel, a support in the cabinet for towels arranged in superposed stacked order, and in position relative to the opening, so that the topmost one can be withdrawn through said opening, means mounting the support for rotation within the cabinet, means mounted for rotation within the cabinet, a forwardly tiltable frame supporting said mounting means, means mounted for rotation and tilting with the support for engaging the edge of the towels nearest the opening to prevent complete withdrawal of towels through the opening, releasable means to tilt the frame forwardly whereby to move the topmost towel close to the opening for withdrawal therethrough, and means controlled by and functioning with the release of said last named means to rotate the support; there being a slot in the front wall of the cabinet depending from the leading end of the opening relative to the direction of rotation of the support to receive the towel edgewise with such rotation and when said towel is hanging from the opening on the outside of the cabinet.

4. A towel servidor comprising a cabinet having a horizontal opening in its front wall for the withdrawal of a towel, a support in the cabinet for towels arranged in superposed stacked order, and in position relative to the opening, so that the topmost one can be withdrawn through said opening, means mounting the support for rotation within the cabinet, means mounted for rotation within the cabinet, a forwardly tiltable frame supporting said mounting means, means mounted for rotation and tilting with the support for engaging the edge of the towels nearest the opening to prevent complete withdrawal of towels through the opening, releasable means to tilt the frame forwardly whereby to move the topmost towel close to the opening for withdrawal therethrough, and means controlled by and functioning with the release of said last named means to rotate the support; there being a slot in the front wall of the cabinet depending from the leading end of the opening relative to the direction of rotation of the support to receive the towel edgewise with such rotation and when said towel is hanging from the opening on the outside of the cabinet.

- tion with the support and engaging the edge of the towels nearest the opening to prevent complete removal of the towels from the cabinet, means normally covering the opening, manually operable means including a depressible pedal to uncover the opening for the withdrawal of a towel, and functioning upon the depression of the pedal, and means functioning with the retractive movement of the pedal for rotating the support 10 in one direction; there being a slot in the front wall of the cabinet depending from the leading end of the opening relative to the direction of rotation of the support to receive the towel edge-wise with such rotation and when said towel is 15 hanging from the opening on the outside of the cabinet.
4. A towel servidor including a cabinet having a horizontal front-wall towel dispensing opening, said wall having a depending slot at one end of 20 and communicating with the opening, a rotatable support for a stack of towels mounted within the cabinet, means associated with the support and rotatable therewith to engage the towels at their edge nearest the opening to prevent complete withdrawal of a towel through the opening, and means to rotate the support in the direction of 25 said slot whereby after a towel has been withdrawn through the opening and is hanging down on the outside of the cabinet, it will pass edgewise through the slot and back into the cabinet with the rotation of the support.
5. A towel servidor comprising a cabinet having a horizontal towel dispensing opening in its front wall, a rotatable support for a stack of towels 30 disposed within the cabinet, in position accessible to the opening, means associated with the support to engage alternate towels of the stack on their opposite edges, said edges being those parallel to the opening whereby a towel uppermost on the stack and whose engaged edge is that nearest the opening may be pulled out through the opening, and manually controlled means to rotate the support through a half revolution at a time.
6. A towel servidor comprising a cabinet having a horizontal towel dispensing opening in its front wall, a rotatable support for a stack of towels 35 disposed within the cabinet, in position accessible to the opening, means associated with the support to engage alternate towels of the stack on their opposite edges, said edges being those parallel to the opening whereby a towel uppermost on the stack and whose engaged edge is that nearest the opening may be pulled out through the opening, means normally closing the opening, manual means movable from a predetermined position for opening said closing means, and means controlled by the return of said manual 40 means to said position for rotating the support a half turn.
7. A towel servidor comprising a cabinet having a horizontal towel dispensing opening in its front wall, a vertical frame hinged along its front lower edge in the cabinet for forward tilting movement, a vertical shaft turnably mounted in and projecting upwardly from said frame, a support for a stack of towels mounted in connection with said shaft for rotation therewith, said towels when the frame is tilted forwardly being accessible to the opening for withdrawal, a depressible pedal, means between the pedal and frame to tilt the latter when the pedal is depressed, and means 45 between the pedal and shaft and functioning to rotate the shaft a predetermined amount only with the retractive movement of the pedal.
8. A towel servidor comprising a cabinet hav-
- ing a horizontal towel dispensing opening in its front wall, a vertical shaft rotatably mounted in the cabinet, a support for a stack of towels mounted in connection and turnable with the shaft, said towels being on a level with the opening, a manually operable lever, a ratchet wheel fixed on the shaft, a drum turnable on the shaft and having a pawl to engage the wheel, means functioning with the movement of the lever in one direction to rotate the drum a predetermined amount in a direction such that the pawl will not 50 rotatably engage the wheel, and a spring placed under tension by such rotation of the drum and tending to turn the same in the opposite direction.
9. A structure as in claim 8, with stop means normally preventing rotation of the shaft, and means actuated by the return of the lever to its initial position to release said stop means.
10. A towel servidor comprising a cabinet having a horizontal towel dispensing opening in its front wall, a vertical shaft rotatably mounted in the cabinet, a support for a stack of towels mounted in connection and turnable with the shaft, said towels being on a level with the opening, a manually operable lever, a ratchet wheel fixed on the shaft, a drum turnable on the shaft and having a pawl to engage the wheel, a pivoted arm connected to the lever to be swung through a certain arc with the movement of the lever in one direction, a cable wrapped about and secured to the drum, one end of the cable being secured to the arm, and a tension spring between and connecting the other end of the cable to said arm.
11. A structure as in claim 7, with a fixed vertical stop in the cabinet, a fixed stop on the frame immediately beyond said first named stop in the direction of rotation of the shaft, and a stop movable parallel to the shaft and mounted in connection therewith for successive engagement with 40 said fixed stops.
12. A towel servidor including a cabinet having a towel dispensing opening in one wall, a supporting plate for a stack of towels disposed within the cabinet, vertical rods disposed in a plane parallel to and spaced from said wall on which the plate is guided, means urging the plate upwardly, said rods passing slidably through the towels adjacent one edge thereof and being formed with outwardly and downwardly bent hook portions 50 on their upper ends.
13. A towel servidor comprising a cabinet having a towel dispensing opening, a movable cover normally closing the opening, towel supporting means in the cabinet, a depressible pedal, means between the pedal and cover to open the latter by a depressing of the pedal to expose a towel for manipulation by the user, spring means tending to close the cover, and means included with said cover opening means to allow the spring action 60 to slowly close the cover while the pedal is maintained depressed.
14. A towel servidor comprising a cabinet having a towel dispensing opening, a movable cover normally closing the opening, a spring acting to 65 close the cover, towel supporting means in the cabinet, a depressible pedal, and means between the pedal and cover to open the latter with a depression of the pedal and including longitudinally aligned links and a dash pot interposed between and connected to the adjacent ends of the links, said dash pot arranged to yieldably resist the action of the spring.
15. A towel servidor comprising a cabinet having a horizontal towel dispensing opening in its

front wall, a rotatable and forwardly tiltable support for a stack of towels disposed within the cabinet, in position accessible to the opening, means associated with the support to engage alternate towels of the stack on their opposite edges, said edges being those parallel to the opening, releasable means to tilt the support forwardly whereby the topmost towel will be moved adjacent the front wall of the cabinet so that said 10 towel may be pulled through the opening, and means acting on the support and functioning with the release of said first named means to rotate the support through a half revolution.

16. A towel servidor comprising a cabinet having a towel dispensing opening, a towel support rotatably mounted in the cabinet, means on the support to hold a stack of towels in opposed relation so that the top towel may be withdrawn through the opening when the support is in one 20 position and the next towel when the support is rotated a half turn, means to rotate the support a half turn at a time, and means whereby with such rotation a used towel projecting through the opening and hanging down the outside of the 25 cabinet will be completely returned to the interior of the cabinet.

17. A towel servidor comprising a cabinet having a towel dispensing opening, a normally closed cover for the opening, a towel support rotatably

mounted in the cabinet, means on the support to hold a stack of towels in opposed relation and so that the top towel may be withdrawn through the opening when the support is in one position and the next towel when the support is rotated a half turn from such position, a depressible pedal, means between the pedal and cover to open the latter with the depression of the pedal, and means between the pedal and the support to rotate the latter with the retractive movement of the pedal when released from the foot pressure.

18. A structure as in claim 17, with means incorporated in part with the cover opening means to cause the cover to move to a closed position while the pedal is held depressed.

19. A towel servidor comprising a cabinet having a towel dispensing opening, a normally closed cover for the opening, a towel support in the cabinet movable between two positions, means on the support to hold a stack of towels in such relation to each other that successive towels can only be withdrawn through the opening when the support is moved from one position to the other, means to open the cover, means to thus move the support, and manual means to operate the cover opening means and the support moving means in successive order.

AUGUST I. HONDEVILLE.
